PRODUCTION OF STOCKINGS FROM REIN-FORCED WARP FABRIC

Richard Richter, Oberlungwitz, Saxony, Germany; vested in the Alien Property Custodian

Application December 5, 1940, Serial No. 368,596
In Germany March 16, 1938

2 Claims. (CL. 66—86)

This invention relates to stockings provided with reinforced foot portions and cut from warp fabric, and to a method of producing same.

In the known kinds of stockings cut from warp goods having worked-in reinforcements the foot comprises two or three parts united by seams, depending upon whether the leg together with the instep, the heel portions and the upper toe portion is cut out as a unit to which the sole cut together with the lower toe portion from a second piece of goods is then attached, or only the leg with the instep and the heel portions is cut from a partially reinforced piece of warp fabric and the sole and lower toe portion as well as the upper toe portion constitute separate members. In both instances, the fabric from which the legs are cut is reinforced in those parts that subsequently are to form the high heel and heel portions. When stockings are to be made in which the upper toe portion is to be seamlessly united with the instep or front foot portion, the leg must also contain a corresponding reinforcing zone for this purpose. It need hardly be pointed out that on account of their bothersome manufacture these known stockings are quite expensive, apart from the fact that the seams required for uniting the various parts of a stocking are often highly undesirable.

It is the object of the invention to overcome these drawbacks at present found in stockings cut from warp goods having worked-in reinforcements by providing each of the foot portions on the sides of the instep with undivided reinforcing pieces of fabric which are seamlessly united with the instep and cover the toe, one-half of the sole, a heel portion and a high heel portion of the stocking.

A stocking made according to the invention is therefore the equivalent of a stocking with a French foot worked on a flat knitting frame in the usual manner, that is to say, it consists of a single piece, whereby all the defects of the known stockings cut from warp goods are eliminated.

Into the fabric serving for the production of stockings according to the invention a reinforcement is worked for the high heel, heel, sole and toe of each stocking, which forms a unit, whereas in the fabric from which the leg with the instep, the heel portions and possibly the upper toe portion of the known stockings are cut not even the reinforcement for the high heel, heel and upper toe portion constitutes a unitary connecting surface and the reinforced sole and lower toe portions are not seamlessly united with the instep or front foot portion of the reinforcement

5 for the high heel, heel and upper toe portions. Furthermore, the longitudinal boundaries of the reinforcing areas in a fabric used for stockings according to the invention must extend non-rectilinearly, whilst the reinforcing zones in fabric widths for known stockings always have a rectangular or square cross section with the longitudinal edges extending parallel to the wales of the fabric.

10 This form of the reinforcing areas in a warp knitted fabric requires a special method for working the reinforcing warp threads, which constitutes another feature of the invention and consists in starting at the places to be reinforced 15 separate warp thread groups which, in addition to lapping, for the purpose of producing reinforcements having non-rectilinearly extending longitudinal edges, perform lateral inward or outward motions corresponding to the desired outline of the inner longitudinal edges of the reinforcements.

It is admittedly not novel per se to provide in the manufacture of stockings from warp fabric for lateral inward or outward motions of the 20 reinforcing warp thread groups in addition to their lapping motions. This step is carried out also in methods for producing warp knitted goods or stockings with French feet, though only regularly worked stockings have been made hitherto in this manner. For example, one of the known methods aims to produce a regular tubular stocking on a warp loom having two rows of needles and for this purpose provides for working one-half of the stocking on each needle row in regular fashion and, by means of the reinforcing thread groups which are laterally moved inwardly or outwardly during their lapping action, causes in each half a reinforcing area to be 25 knitted which continually comprises a high heel portion, a heel portion, a sole portion and half a toe. According to another known method of producing a regular stocking with French foot on a warp machine the procedure is such that the warp forming the stocking is subdivided into 30 several single thread groups guided on different planes and the outer groups are correspondingly moved inwardly for narrowing so as to have adjacent thread groups overlap one another. In this case, too, the finished stocking will have two 35 reinforcing areas, each of which forms a connecting reinforcement for the high heel, heel and sole portion and half of the toe.

The two known methods mentioned have, however, nothing in common with the method according to the invention, not only because they

refer to the manufacture of warp knitted stockings made in regular fashion, but chiefly for the reason that their application does not yield fully satisfactory stockings. According to the last-mentioned method for instance, reinforcements are formed by the lateral inward motion of the outer thread groups, since in this way adjacent thread groups overlap one another. It is evident that no reinforcing structures can be produced in this manner, which will coincide with the form of the high heel, heel, sole and toe reinforcement of regular stockings. The form of the reinforcements depends therefore upon how the outer warp thread groups are moved in, which is done so as to impart to the outer edges of the blank the necessary outline, since otherwise a full fashioned stocking could not be formed. The result, however, is that the inner longitudinal edges of the reinforcements extend exactly parallel to the outer longitudinal edges of the fabric, which is at least considerably at variance with the form of the reinforcement of the foot of regular stockings. It should also be taken into consideration that the reinforcements of stockings made in this manner consist of thread material of the same kind as that of the leg. This is a disadvantage, since for reinforcing the foot portions a special thread is used as a rule.

A stocking made according to the first-mentioned known method lacks usefulness for the reason that the two halves of the stocking are connected at their longitudinal edges by a narrow thread group. These two narrow thread groups, in contradistinction to the thread groups producing the two halves of the leg, operate on both needle rows, so that a seamlike edge is formed in the front and rear portions of the finished stocking. In this instance, too, the reinforcements are produced from threads which previously participate in knitting the leg and therefore often, as in case of artificial silk stockings, lack the necessary resistance.

This brief review of the art indicates that it is not known at present to produce a warp knitted stocking corresponding to one of the usual stockings with French foot made on a flat knitting frame. The invention provides such a possibility for the first time and in doing so puts an end to the prejudice that a warp knitted stocking in order to be like a regular stocking with French foot made on a flat knitting frame should be produced in full fashioned manner on a warp machine. This is of special importance in view of the fact that the object of the invention cannot be attained by regular working, but only by moving the reinforcing warp thread groups laterally in and out in such manner that the reinforcements disclose the inner limitation found in regular stockings. That a stocking made according to the invention possesses cutting edges is absolutely immaterial, since it is possible to produce on a warp machine fabrics which prevent the formation of ladders, so that the longitudinal edges of the stocking need not be as close as the corresponding edges of stockings made on flat knitting frames.

It may further be mentioned that the known method of producing a tubular stocking on a warp machine is impracticable also for the reason that during reduction of the width of the fabric non-working of the warp threads lying outside the outline of the stocking is to be effected by drawing down the needles concerned. As this prevents the arrangement of the warp threads on a common warp beam, it would be necessary to

provide for each warp thread a separate bobbin, etc., which is of course impossible considering the number of warp threads that goes into the making of a stocking. Furthermore, a warp machine operates economically only if several stockings can be made thereon side by side, so that the number of thread spools would have to be increased still more.

The invention is illustrated by way of example in the accompanying drawing, in which—

Figure 1 shows a piece of warp fabric from which the stockings according to the invention are cut; and

Fig. 2 indicates a row of frame needles of a warp machine with their lapping means.

The stocking according to the invention is cut from warp fabric provided with worked-in reinforcements, the arrangement being such that each of the foot portions on either side of the instep is provided with a reinforced undivided piece of fabric seamlessly united with the instep and forming the toe Sp, one-half of the sole So, a heel portion F and a high heel portion H.

As indicated in the drawing, for producing a warp knitted fabric width B for the stocking a warp thread 1 is gathered into the lapping machine 2 to form the ground of the fabric into which the reinforcements H, F, So and Sp are worked by means of separate warp thread groups 3, 4 gathered into separate lapping machines 5, 6. Besides for lapping, these warp thread groups 3, 4 are subjected to lateral inward and outward motions also in accordance with the desired form of the inner longitudinal edges of the reinforcements H, F, So and Sp. The individual stockings are cut out of the fabric worked in the manner described along the outlines indicated by dash-and-dot lines, one stocking S being horizontally hatched in Fig. 1. The stockings S are preferably cut from the fabric B in the usual manner, that is, side by side and one above the other, which makes it necessary, however, to withdraw the reinforcing warp thread groups 3, 4 from the frame needles 7 from the reinforcing point of one course to that of the next. These places are marked by broken lines in the drawing, the lapping machines 5, 6, as indicated in Fig. 2, being merely brought into the broken line position.

As shown in the drawing, the fabric B is knitted so that the toes Sp of the stockings face the initial edge of the goods. The two reinforcing warp thread groups 3, 4 are moved closely together at the toes Sp, are spread apart in the sole portions So and heel portions F, are then moved inwardly to a slight extent at the beginning of the high heel and are subsequently gradually moved outwardly in such manner that at the end of the high heel portions H they are positioned completely outside the stocking forms S to be cut out. In this way, no thread ends will be produced at the high heel portions H by the cutting out of the floating pieces of the threads 3, 4. Inversely, if the fabric B is worked so that the toes Sp of each course face the end edge of the fabric, the two reinforcing warp thread groups 3, 4 start their work in each course in the high heel portions H and are then moved inwardly up to the toe Sp. To avoid thread ends at the reinforcement of the high heel portions H also in this case, the procedure is such that both thread groups 3, 4 are in initial position outside the form S to be cut out and are gradually moved inwardly at the beginning of the reinforcement for the high heel portions H.

The width of the fabric B is immaterial of

course and could be equal also to that of a single stocking. In the drawing, it is assumed to work the fabric B by means of a warp thread 1 and a lapping machine 2. If a ladderproof fabric is to be made, it will be necessary to knit the fabric B with two ground warp threads.

We claim:

1. A stocking cut from warp fabric partly reinforced by separate warp threads, comprising a single undivided piece of fabric constituting a complete foot portion, and a separate reinforcing piece on each side of the instep of the foot portion, said reinforcing pieces being seamlessly

united with the instep and extending over the toe, one-half of the sole, a heel portion and a high heel portion of the stocking.

5. Method of producing warp knitted widths of fabric from which stockings having reinforced foot portions according to claim 1 are to be cut, comprising in causing the separate warp thread groups, for the reinforcements to carry out, besides for their lapping work, lateral inward or outward motions corresponding to the outline desired for the inner longitudinal edges of the reinforcements.
